UNITED STATES PATENT OFFICE.

BENJAMIN M. GRIFFITH, OF PITTSBURGH, PENNSYLVANIA, ASSIGNOR TO NATIONAL CASKET COMPANY, OF PITTSBURGH, PENNSYLVANIA, A CORPORATION OF NEW YORK.

BIER.

Application filed December 29, 1924. Serial No. 758,541.

To all whom it may concern:

Be it known that I, BENJAMIN M. GRIFFITH, a citizen of the United States, residing at Pittsburgh, county of Allegheny, and 5 State of Pennsylvania, have invented a new and useful Improvement in Biers, of which the following is a full, clear, and exact description.

The present invention relates broadly to 10 supports, and more particularly to supports of the character adapted for use in maintaining caskets in a predetermined elevated position during ceremonials and the like.

It has heretofore been proposed, in the 15 art to which this invention relates, to construct biers of a collapsible or extensible nature, whereby they are adapted to be extended for caskets of different sizes and collapsed for convenient handling. The construction of the biers with which I am 20 familiar, however, has not been such as to enable the compact folding which is desirable, and they have further been of such construction, when extensible, as to detract 25 materially from their appearance.

The present invention has for certain 30 of its objects, construction of a bier having sufficient strength and rigidity to adapt it to the purposes for which it is intended, 35 and at the same time so constructed that it is adapted to fold compactly and present an attractive appearance whether folded or extended.

In the accompanying drawings I have 35 shown, for purposes of illustration only, a preferred embodiment of the present invention, it being understood that the drawings do not define the limits of my invention, and that changes may be made in the construction and operation therein disclosed 40 without departing from the spirit of my invention or the scope of my broader claims.

In the drawings:—

Figure 1 is a perspective view of the 45 bier in extended position ready to receive a casket;

Figure 2 is a perspective view of the bier in collapsed position, and

Figure 3 is a detail sectional view, on an 50 enlarged scale, illustrating the means for maintaining the legs in predetermined spaced relationship.

In carrying out the present invention, 55 there may be provided a bier comprising, in effect, an intermediate portion and two

end portions, the intermediate portion being constructed to permit extension for caskets of different lengths, and the end portions comprising the supporting legs.

In a construction of this character, the 60 intermediate portion may conveniently comprise a pair of spaced tubular outer members 2 directly secured at one end to an upright 3, and at the other end maintained in pre-determined spaced relationship by a tubular spreader 4 interconnecting the same. Telescopically mounted within the outer members 2 are inner members 5, each secured at one end to an upright 6 and spaced to freely slide within the outer members.

The uprights 3 and 6 are preferably of 65 similar construction, whereby during the manufacture of the bier, a single pattern may be utilized, thereby facilitating manufacture and permitting interchangeability of the 70 parts during assembly. Each of these supports has formed on opposite sides thereof spaced lugs 7 forming brackets between which are pivotally mounted upper braces 8 and lower braces 9, which braces at their 75 outer ends are secured to legs 10. Preferably the braces 8 and 9 are secured to the uprights in the plane of the outer members, whereby added strength is secured and symmetry of appearance obtained, all of the 80 parts when in use constituting, in effect, continuations one of the other, and when folded lying in side by side relationship, as clearly apparent from Figure 2. The 85 legs are adapted to be folded in opposite 90 directions, whereby when folded, one leg of each pair will lie on opposite sides of the intermediate portion. For holding the legs normally against such folding movement, one of the lower braces 9 of each 95 pair may be perforated to receive the down-turned end 11 of a latch 12, the opposite end of which is turned downwardly to engage a recess 13 in the opposite brace 9 of each pair. In order to permit the latch 100 to be engaged and disengaged, the down-turned portion 11 may be of such length as to permit it to slide freely through the brace 9 to which it is attached, the movement in one direction being limited by a shoulder 14 105 and in the opposite direction by a head 15.

It has been found desirable in practice to so construct and proportion the parts that the legs 10 carry all of the load. For this reason, they are each preferably provided 110

with an extension 16 projecting a slight distance above the plane of the braces 8 and the intermediate portion, thereby relieving the intermediate portion of any strain or any load, such as would tend to distort the tubes and prevent free telescopic movement thereof.

The advantages of the present invention arise from the provision of a bier presenting 10 a pleasing appearance, extensible to accommodate caskets of different sizes and constructed whereby it may be easily and conveniently extended or collapsed with the supporting legs on opposite sides of the intermediate portion.

I claim:

1. A bier, comprising an intermediate portion, uprights at the ends of said intermediate portion adapted to rest on a supporting 20 surface for the bier, brackets on each of said uprights in vertically spaced relation, and oppositely folding legs pivotally mounted in said brackets, substantially as described.
- 25 2. A bier, comprising an intermediate portion, uprights at the ends of said intermediate portion adapted to rest on a supporting surface for the bier, brackets on each of said uprights in vertically spaced relation, and 30 oppositely and individually folding legs pivotally mounted in said brackets, substantially as described.
3. A bier, comprising an intermediate portion, uprights at the ends of said intermediate 35 portion adapted to rest on a supporting surface for the bier, brackets on each of said uprights in vertically spaced relation, oppositely folding legs pivotally mounted in

said brackets, and means for holding said legs in predetermined angular spaced relation against collapse, substantially as described. 40

4. A bier, comprising an intermediate portion, uprights at the ends of said intermediate portion, brackets on each of said uprights in vertically spaced relation, oppositely folding legs pivotally mounted in said brackets, and means for holding said legs in predetermined angular relation, said means being normally carried entirely by 45 one of said legs, substantially as described. 50

5. In a bier, an intermediate portion comprising a pair of tubular outer members and a pair of inner members telescopically co-operating therewith, uprights secured respectively to the ends of said members at one end only, a spreader for the free ends of said outer members, and oppositely folding legs attached to said uprights, substantially 55 as described. 60

6. A bier, comprising an extensible intermediate portion having upper and lower extensible members, uprights at the ends of said members, brackets carried by said uprights substantially in the plane of said members, braces pivotally mounted in said brackets, legs secured to said braces, said legs being oppositely foldable against the sides of said intermediate portion or outwardly into supporting relation, and means 65 for maintaining the same in supporting relation, substantially as described. 70

In testimony whereof I have hereunto set my hand.

BENJAMIN M. GRIFFITH.
